(57) **CLAIM**

The ornamental design for an electrical current measurement module as shown and described.

DESCRIPTION

1. Electrical current measurement module

1.1 : Perspective

1.2 : Front

1.3 : Back

1.4 : Left

1.5 : Right

1.6 : Top

1.7 : Bottom

The parts shown by means of broken lines in the reproductions are not part of the claimed design. The broken lines shown are included for the purpose of illustrating portions of the electrical current measurement module and form no part of the claimed design. The purpose of this design product is electrical current measurement.
